United States Patent Office.

GEORGE WEEDEN FRANCIS, OF HARTFORD, CONNECTICUT, ASSIGNOR TO HIMSELF, EDWIN GARFIELD, AND JEREMY W. BLISS, ASSIGNORS TO THEMSELVES AND GEORGE W. WILLIAMS, OF SAME PLACE.

Letters Patent No. 91,619, dated June 22, 1869.

IMPROVED PROCESS AND APPARATUS FOR MAKING SHEET-IRON.

The Schedule referred to in these Letters Patent and making part of the same.

To all whom it may concern:

Be it known that I, GEORGE WEEDEN FRANCIS, of the city and county of Hartford, and State of Connecticut, worker in iron, have invented a new and useful Process for Treating Sheet-Iron to give the same an enamelled, or polished surface, and also new and useful apparatus for practising the same; and I do hereby declare that the following, taken in connection with the drawings which accompany and form part of this specification, is a description of my invention sufficient to enable those skilled in the art to practise it.

The object of my invention is the production of a quality, or kind of sheet-iron resembling, as nearly as may be, and having the peculiar characteristics of surface-finish, and flexibility, of the well-known Russia sheet-iron.

As my invention does not relate to the rolling of the iron into the form of sheets, nor to any of the processes anterior thereto, but merely to the treatment of the metal when in the sheet-form, none of such processes need be here described.

The iron being then first formed into sheets of the required length, width, and thickness, and being of such quality as may be desired for the degree of finish and excellence to be given it, my invention consists in immersing the sheets in any appropriate acid, for a sufficient length of time to loosen or remove foreign matter from the surface, then heating them to a degree varying from about six hundred and fifty degrees (650°) to about eight hundred and fifty degrees (850°) Fahrenheit, more or less, according to circumstances.

I either beat the sheets separately, that is, separated from each other, but simultaneously with the heating of the box, or I place one upon the other, flatwise, in the as yet uncovered box, and then heat the box and contents together.

In case the sheets are heated separately, as above, they are to be placed within the box before either is withdrawn from the furnace, and then submitted further to action of the furnace, until the proper temperature has been given them.

When the box and contents (whether the latter have been separately heated, or heated only whilst in the box) have received the proper degree of heat, the box (preferably before being taken from the furnace) is to be covered by a suitable metallic cover, to prevent, as much as possible, exposure of the contents to the action of the atmosphere, and then withdrawn from the furnace, and the sheets immediately subjected to the direct blows of a set of rapidly automatically operated hammer or hammers, the cover and parts being so arranged and actuated, that the hammers may act through the cover, and directly upon the entire upper

surface of the top of the pack of sheets, and that the heat and gases shall be confined, as far as practicable, within the box during the hammering-process.

The better to convey a more accurate idea of my process, I will now proceed to describe a simple form of machine, which will serve to illustrate one way in which it may be practised, although it will be evident that the apparatus may be varied in many ways, and yet still be adapted for practising my process.

In the drawings—

Figure 1 represents a side view, and

Figure 2, a longitudinal vertical section of such an apparatus;

Figures 3 and 4 representing, respectively, the box and one of its removable covers, or bottoms, designed for holding a number of sheets to be treated, and which lie flat therein, each upon the other.

A represents an oven, or furnace, of any appropriate form of construction suitable for imparting to the separated sheets, and to the box, or to the box and its contained sheets, as the case may be, the required degree of heat.

B are guide-rails, or flanges, serving to keep the box C in proper position when the sheets are under the action of the hammer or hammers, and also to guide the same when shoved into or withdrawn from the furnace.

The portion marked D D, immediately under the box, and beneath where the blows of the hammers fall, should be made solid and firm, of iron or other appropriate material, to serve the purpose of an anvil; and the space marked E, between the box and the furnace, should be much greater than shown in the drawings, in order to allow sufficient room to swivel and handle the box, as hereinafter stated.

This portion, or bed D, need not, necessarily, be continuous, as shown in the drawings, but may, between the anvil-portion and the furnace, be open, (except the guides, or rails,) to allow of easy access for any purpose.

The box C is made of strong metal, adapted for withstanding the heat and the shocks to which it may be subjected, and is formed open, both at top and bottom, and with removable pieces F, serving to close up either side, (or both, for a purpose hereinafter stated,) the pieces F being formed, preferably, with rebates, as shown, to secure a closer fit, and with pins f, to receive a clamp, or hook, c, on either side of the box, and which thus hold the parts together.

Handles G, on opposite ends of the box, by means of openings g therein, allow of the boxes, when heated, being shoved or pulled into or from the furnace; and knobs, or centres g', on these handles, allow the boxes to be lifted and turned over, whenever it may be

thought advisable to reverse the pack, and hammer the opposite side thereof.

Any ordinary mode of lifting, by crane, pulleys, or otherwise, may be used for this purpose.

Whenever such reversing of the box and its contents is desired, a top like F is put on; the box is then turned over, its former bottom is taken off, and the long top H, shown in figs. 1 and 2, substituted therefor, and the hammering resumed.

This top, or cover H is made of flat metal, with its sides turned down, as shown at h, so as to cover the joint between it and the box, and it is made of sufficient length to permit its being slid on the box, so that the hammers may, with it, traverse the length of the sheets, to operate upon the entire surface; and is is also provided with a transverse opening, barely sufficient to afford space for the hammers to work through, to reach the top sheet, the cover, except at this opening, closely confining the heat and gases within the box.

I represents one of the beams of the mill, or factory, or of any other appropriate frame-work, which serve as supports for sustaining the hammer or hammers, the frame for guiding them, and devices for actuating and feeding them forward.

Upon each of two of such beams, I place a toothed rack, K, from which is suspended the frame, or hangers L, in which the hammers M M play, (of any number desired.)

Upon this hanger is a shaft, N, driven from its pulley O; cams, or wipers P P, on the same shaft, serving, during its revolutions, to lift, or trip the hammers rapidly and successively.

To the hangers are attached hooks Q Q, which are intended to connect with staples R R, on the long sliding cover H, so that as the progressive movement of the hammers shall positively move the cover coincident, the hammers may always play freely through the slot therein.

Attached to the travelling hangers L, are feeding pawls S S, for feeding the hammers forward or back, as the case may be, these pawls being operated, by cranks T T, on rock-shaft U U, which receives motion, from the rising shaft of the hammers, through the medium of arms V V, secured to said shafts U U.

When feeding in one direction, the pawl not needed is simply thrown up out of contact with the rack, as shown in the figures. This may be done by a cord and pulley, or any other simple means.

The hammer-driving pulley O, I connect with the main shaft, or source of power, by means of a knuckle-joint frame, so as to permit the shaft N, with the hangers on which it is supported, to move to and from the main shaft, without impairing its proper revolving action.

The operation is as follows:

The furnace being heated, the sheets of iron and the box are placed within it, the sheets either lying flat within the uncovered box, as heretofore stated, or if not so disposed, then each supported, by any convenient means, in somewhat of a vertical position, the box being also heated at the same time. After both the sheets and box are properly heated, about to the degree heretofore mentioned, they are not pulled out of the furnace until the sheets, if separately heated, have been placed within the box, and the long sliding cover first placed over the same.

When the cover has been first hooked to the hangers, the box has been drawn out far enough to bring the slot in the cover H, and also the hammers, directly over one end of the top-lying sheet in the box.

The hammering-machinery is put in operation by means of pulley O, the appropriate pawls for feeding

in the right direction, being first put into connection with the rack.

The action of the pawls causes a regular intermittent progressive motion to be given to the hanging frame and the hammers, whilst the revolution of the shaft N, causes the latter to be rapidly tripped.

When the hammers have thus traversed from end to end of the sheets, by merely lifting pawls S, and dropping pawl S', (or *vice versa*, as the case may be,) the hammer-frame traverses in the reverse direction, and this may be continued for any length of time desired.

Whenever, from the greater number of sheets placed at one time in the box, or for any other reason, it may be desired to turn the box and its contained sheets upside down, so as to impart the blows to the opposite side of the pack of sheets, the knobs, or centres g, upon the handles, as heretofore stated, admit of doing this with facility, by any simple provision which will lift the box, by these handles, high enough to allow it to be turned half over, or upside down, and then placed upon the anvil, to undergo a similar operation of hammering.

The time required for the hammering of the sheets may be fifteen minutes, more or less, varying with the quality and quantity of the iron under treatment, the size or thickness of the sheets, or the size, power, and rapidity of the blows of the hammers.

It is apparent, that numerous variations and modifications of the described machine may be made, without departing from the spirit of the invention contained therein. For example, instead of causing the frame and hammers to traverse forward and back, the box and contents may be made, or caused so to traverse by any well-known means. The hammers may also be given a reciprocating sidewise traverse, as well as a forward and backward one, or the box may have a sidewise reciprocation, either with or without an endwise one. Each hammer, also, need not extend across the breadth of the sheet, but a series of hammers, all acting together, or in quick succession, may be used instead, and any desired number of hammers may be employed.

I believe I have thus stated the nature and mode of operation of my invention, so as to enable others skilled in the art to practise the same therefrom.

What I claim, and desire to secure by Letters Patent, is—

The process for producing a polished, or enamelled surface upon sheet-iron, substantially as herein described.

Also, a series of automatically-operated hammers, acting directly upon the pack of enclosed sheets, substantially as described.

Also, a series of automatically-operated hammers, having, in addition, a travelling motion over the face of the material to be treated, substantially as set forth.

Also, a travelling frame, for supporting the hammers, arranged to be automatically traversed forward or backward, at will, substantially as set forth.

Also, as a container for the sheets to be treated, a metal box, with removable bottom, or bottom and top, arranged to be fastened or clamped thereto, substantially as set forth.

Also, in combination with the hammers and the sheet-containing-box, the slotted cover, arranged to permit the traversing movements during the hammering, substantially as set forth.

GEORGE W. FRANCIS. [L. S.]
